WIND MEASURING INSTRUMENT

Richard N. Motsinger, 4409 N. 38th St., Phoenix, Ariz.

Filed Oct. 2, 1961, Ser. No. 66,940

Term of patent 14 years

(Cl. D52—6)

The single FIGURE is a perspective view of a wind measuring instrument showing my new design; with a portion broken away for convenience of illustration.

I claim:

The ornamental design for a wind measuring instrument, as shown and described.
